CLAIM

The ornamental design of a product display component, as
shown and described.

DESCRIPTION

FIGS. 1-13 illustrate a design for a product display component according to a first embodiment of the invention in which:

FIG. 1 is a perspective view thereof;

FIG. 2 is front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is an exemplary perspective view of several instances of the first embodiment mounted on a support and arranged in a multi-unit display assembly, and without any separation between the break lines;

FIGS. 9-13 illustrate the first embodiment with the pusher plate in an alternate position and showing products contained in the display component, in which:

FIG. 9 is a perspective view thereof;

FIG. 10 is a left elevational view thereof;

FIG. 11 is a right elevation view thereof;

FIG. 12 is a top plan view thereof; and

FIG. 13 is a bottom plan view thereof.

FIGS. 14-26 illustrate a design for a product display component according to a second embodiment of the invention in which:

FIG. 14 is a perspective view thereof;

FIG. 15 is front elevational view thereof;

FIG. 16 is a rear elevational view thereof;

FIG. 17 is a left elevational view thereof;

FIG. 18 is a right elevational view thereof;

FIG. 19 is a top plan view thereof;

FIG. 20 is a bottom plan view thereof;

(Continued)

FIGS. 21-25 illustrate the second embodiment with the pusher plate in an alternate position and showing products contained in the display component, in which:

FIG. 21 is a perspective view thereof;
 FIG. 22 is a left elevational view thereof;
 FIG. 23 is a right elevation view thereof;
 FIG. 24 is a top plan view thereof; and,
 FIG. 25 is a bottom plan view thereof.

The broken lines in the drawings represent portions of the display component that form no part of the claimed design. Dot-dash-dot lines are used to illustrate exemplary environment of use. The separations and brackets are used to indicate features of varying lengths, wherein the appearance of any portion of the product display component between the break lines forms no part of the claimed design.

1 Claim, 25 Drawing Sheets
